UNITED STATES PATENT OFFICE

AUGUSTUS J. SACKETT, OF ANNE ARUNDEL COUNTY, MARYLAND, ASSIGNOR TO THE
A. J. SACKETT AND SONS COMPANY, A CORPORATION OF MARYLAND

FERTILIZER-SCREEN VIBRATOR

Application filed April 16, 1929. Serial No. 355,462.

The invention relates to screens of the type used in the grading or screening of ground or comminuted materials, the apparatus to which the invention is applied being particularly adapted to the treatment of fertilizer materials, though it is also adapted to use in the grading or screening of various materials as sand, lime, ground shell or the like. The screen to which the invention is applied 10 is of the rotary or oscillating type and preferably of arcuate or cylindrical form.

In the screening operation the meshes or screen apertures are in the treatment of the majority of the materials handled, subject to 15 partial or complete clogging by the retention therein of an accumulation of fine dust or of particles which fit or nearly fit the screen openings or mesh or otherwise.

The expedient of vibrating the screen to 20 overcome this difficulty is present and more or less familiar in the various branches of the screening art. The majority of these vibrating devices are comparatively complicated and inclined to get out of order so that 25 they require attention from time to time and many of those which are effective are high speed motor driven vibrators which in their operation consume an amount of power which is a considerable proportion of that required 30 in the main operation of the machine, i. e., in rotating or oscillating the screen and feeding the material when and if it is fed automatically.

The invention relates to the provision of 35 a vibrator for a rotating or oscillating screen of simple, and substantial construction which can be produced cheaply and which is not apt to get out of order and which at the same time is operated without the expenditure of 40 any power in addition to that required to rotate or oscillate the screen.

In the accompanying drawing I have illustrated 45 a fertilizer screen embodying the features of my invention in the preferred form.

In the drawings:

Figure 1 is a perspective view of a fertilizer screen of the rotary or oscillatory type, one of the trays or sections being removed to disclose the vibrator with which it is equipped.

Figure 2 is a side elevation of a screening machine assembled for operation.

Figure 3 is an end view of the screen cylinder showing one of the spiders comprising the screen frame and the vibrators cooper- 55

Figure 4 is an elevation on an enlarged scale of one of the vibrators removed, the same being taken in the direction of Figure 3, and

Figure 5 is an elevation of the same vibrator taken at right angles to Figure 4.

Referring to the drawings by numerals each of which is used to indicate the same or similar parts in the different figures, the apparatus illustrated comprises a screen member 1 in the form of a container of foraminous material 2, as wire mesh or screen cloth, though any variety of foraminous material may be used. This screen member 1 as shown 70

is cylindrical in form though it may be of any convenient shape and mounted on a shaft 3 by means of which it may be rotated or oscillated in any suitable manner, the supporting frame and gear connections being 75

obvious and well known in the art and forming no part of the present invention. The screen shown has a normal speed of about twenty revolutions per minute, and it may be driven by a large bevel gear 4 on shaft 3, 80

which bevel gear 4 is engaged by a smaller bevel gear 5 driven by a pulley 6 which is, in its turn, driven by a belt 6". The screen member or container 1 as shown is formed with a feed opening 7 concentric with the axis, i. e., with the shaft 3 through which 85

opening the material to be treated may be introduced, and the outer wall of the container or screen member is shown as comprising a series of sections or trays 8, which 90

as shown are of segmental form and supported in any suitable and convenient manner as by means of spiders or radial frame members 9 secured to the shaft 3 and consisting each of a hub 10 most conveniently split as shown, so that it may be mounted on the shaft without passing over the end and provided with a convenient number of radiating arms 11 to the ends of which the frames 12 of the sections 8 are secured in any suitable and convenient manner as by means of bolts 14 passed through the ends of the arms 11 and through the frames 12.

In the form of the invention shown, the vibrators or strikers to be described cooperate with the spiders or frame members 9 and particularly with the radial arms 11 thereof. These vibrators may be arranged as to these various details to suit the conditions in hand.

20 In accordance with the preferred form shown they consist each of a pendulum-like member 15 including a weight or hammer member 16 and an arm 17 to one end of which the weight is secured, the other end of the 25 arm 17 being pivotally mounted at 18 to permit the arm to swing relatively to the shaft.

In the form of the invention shown, each weight is provided with two arms 17 (see 30 Figure 5) placed side by side and pivotally connected at their inner ends to split collars 19, two of said collars being in the form of the invention shown, provided for each spider. These collars 19 are most fully illustrated in Figures 1 and 3, there being one 35 of said collars on each side of each hub 10 of each spider. These collars are preferably split for convenience in assembling so that they need not be passed over the end of the 40 shaft, and as shown, particularly in Figure 3, the halves of each collar are provided at their meeting edges with flanges 20 secured together in mounting the collars on the shaft by means of bolts 21.

45 The arrangement described, which is shown in side elevation in Figure 5, provides in the instance of each striker or pendulum member 15 a pivotal support for the inner ends of each pair of arms 17 at 18 on each 50 side of the hub member 10 of the corresponding radial frame or spider 9 so that each one of the weights or strikers 16 is located in the plane of the radial arms 11 of the frame and between two adjacent arms 11 so that it can 55 swing into contact with either and from one to the other, its path of oscillation being thus limited.

In the form of the invention shown there 60 are three of the striker members or elements 15, for each frame member or spider 9 and each of these frame members has six radial arms 11, and in accordance with the preferred arrangement illustrated, there is one striker element or member 15 in every alternate space 65 22 between the radial arms 11 though this

number and the arrangement of the spider and other details may be varied to suit the requirements and there are preferably a plurality of sets of striker members or elements, one cooperating with each radial frame or spider 9.

In the operation of the machine, the screen container 1, is driven in any suitable manner. In accordance with the normal operation of the machine illustrated, the screen member 1 is driven in rotation at a speed which may be described in round numbers as approximating twenty revolutions per minute for the six foot cylinder. While the speed is not primarily essential, the device of the invention operates most efficiently with a slow motion of the screen, particularly when the screen is driven in rotation.

With a slow motion of the screen as described, the striker members 15 are operated mainly by gravity cooperating with the motion of the screen so that the weights 16 strike against the radial members 11, each of said members 15 being operated to give two such strokes or blows for each revolution.

Assuming that the cylinder rotates in a right handed or clockwise direction as seen in Figure 3, the cycle of operations of any one of the striker members 15 is as follows, taking for example the member 15 which is hanging downwardly in vertical position in Figure 3. As the cylinder rotates, this member 15 is carried upwardly and to the left by the arm 11 of the spider with which it is shown in contact until it passes the top center and becomes overbalanced on the righthand side of the pivot 18, at which time it swings downwardly and to the right away from said arm 11 as illustrated in dotted lines in Figure 3, there being no striker member occupying the position, relatively to the other strikers shown of the one shown in dotted lines in this figure. At the end of the stroke the middle point or substantially the middle point of which is illustrated in Figure 3, in dotted lines, the weight 16 comes in forcible contact with the radial arm 11 below the striker 15 as shown in dotted lines, imparting a corresponding vibration to the screen cloth or foraminous material 2 supported on the ends of these arms 11, and completing the primary working stroke.

At the completion of this stroke the weight 16 of the striker member 15 remains in contact with the arm 11 below it and which it has just struck, until it has moved downwardly and to the left past the bottom center position. It will be understood that at this time the striker member 15 is on the right hand side of the corresponding radial arm 11, i. e., on the rear side in the direction of rotation. After it passes the bottom center and moves upwardly and to the left through a certain arc its slight momentum and inertia being overcome by the force of gravity, it swings backwardly in

lefthanded revolution toward the next radial arm 11 in this direction. It will be understood that at the same time this radial arm 11 to the rear of the weight moves forwardly 5 in right handed rotation so that the rearward motion of the striker member and the forward motion of the radial arm 11 of the spider are combined to bring these two members in contact and effect a secondary blow 10 or stroke of less magnitude than that accomplished by the same striker immediately after it passes the top center.

The operation of each of the strikers is identical with that of the single striker as 15 just described so that each striker comes in contact with the spider twice in each revolution, giving it a cycle of operations comprising a primary stroke, blow or vibration and a secondary stroke of less magnitude than the 20 primary stroke. In this way with the cylinder rotating at a speed of twenty revolutions per minute which has been assumed for example and each spider being equipped with three strikers, which number has also been 25 assumed for example, the strikers cooperating with each spider will give one hundred and twenty blows or vibrations per minute. For convenience of illustration and to show that there are normally a plurality of sets of 30 strikers cooperating with a plurality of spiders in each cylinder, the present apparatus is shown as equipped with two spiders each cooperating with a set of three strikers so that operating as described the vibrating 35 elements will produce two hundred and forty vibrations per minute, eliminating any and all tendency of the apparatus to become clogged by accumulation of material in the screen apertures. It will be further noted, 40 as already pointed out, that the operation of the vibrator is incidental to the operation of the rotary screen requiring no additional power and that it is further of simple and cheap construction and practically incapable 45 of getting out of order.

I have thus described specifically and in detail an apparatus embodying the features of my invention in the preferred form in order that the nature and operation of the 50 same may be fully understood. However, the specific terms herein are used descriptively rather than in a limiting sense, the scope of the invention being defined in the claim.

55 What I claim as new and desire to secure by Letters Patent is:

The combination in a fertilizer screening machine of a rotating cylinder having walls of foraminous material, the cylinder having 60 a central shaft and radiating spokes supporting the foraminous material, a flange surrounding the shaft on each side of the spokes of one set and a plurality of swinging pendulumlike weights each located between two 65 adjacent spokes, a pair of arms supporting

each of said weights, one on each side of the spokes and immediately adjacent the same, each said arm being pivotally mounted at one end on one said flange whereby each weight is permitted to swing in the plane of the 70 spokes from one spoke to the next causing each weight to vibrate from one spoke to the other as the screen rotates, coming in contact with each of said spokes alternately and vibrating the screen.

Signed by me at Baltimore, Maryland, this 13th day of April, 1929.

AUGUSTUS J. SACKETT.
